UNITED STATES PATENT OFFICE.

VINCENT CRANE RICHMOND AND GEORGE HERBERT SCOTT, OF CARDINGTON, ENGLAND.

AIRSHIP.

Application filed December 15, 1927, Serial No. 240 303, and in Great Britain October 12, 1926.

This invention relates to lighter-than-air craft of the type wherein the gashags or cells are carried inside a rigid or semi-rigid hull framework, the whole being encased in a flexible or semi-flexible cover composed of panels of fabric, and more particularly the invention relates to methods of or arrangements for obtaining and maintaining tautness in the cover.

According to an existing method, the panels of fabric are laced to the hull framework by hand as tautly as possible. Sufficient tension cannot be obtained by this method to prevent the cover from bulging or flapping under the pressure of the atmosphere when in flight, and it is customary therefore to apply doping medium to the cover when in place to cause it to shrink and increase its tension.

Owing to the large area of the cover involved and the difficulty of access to all parts of its surface, this process of doping in situ is costly and unsatisfactory. A further objection is that in the process of time and under the action of weather on the fabric, the cover becomes slack, and the speed of the airship is reduced owing to the irregularities of surface which arise from a slack cover. The only remedy then is to re-dope the cover which adds unnecessary weight to the ship and is a costly process.

According to the present invention, the tautening of the cover in an airship is obtained by mechanical means instead of through the shrinking action of a dope. In consequence, it is immaterial, for the purpose of tightening, whether any doping or the like treatment for the fabric is applied before or after the panels are laced to the hull.

One advantage of applying the doping or the like treatment to the fabric before the panels are made up and laced to the hull is that this treatment may be carried out by mechanical spreading machines, under controlled conditions of atmospheric temperature and humidity, which give a smoother, a more efficient and more chemically stable coating than can be obtained by brushing on dope or other medium by hand, when the panels are in place, in the ship shed where the conditions cannot be controlled.

Broadly stated, the mechanical means of tautening employed according to the present invention are adapted to force the cover fabric inwards or outwards relatively to the airship hull, from what would be the normal

position, in a direction perpendicular or approximately perpendicular to the surface of the fabric.

The invention is illustrated diagrammatically and by way of example in the accompanying drawings, in which Figs. 1 and 2 are a transverse section of two panels of the hull framework of an airship, showing two forms of construction of the present improvements; Figs. 3 and 4, 5 and 6, 13 and 14 are transverse sections of modified forms of construction; Figs. 7 and 8 are plan views of Figs. 5 and 6; Figs. 9 and 10 are plan views of modified forms of construction; Fig. 11 is a longitudinal section of one panel of the hull framework of an airship showing a modified form of construction; Fig. 11^a is a diagram of bending moments; and Fig. 12 is a perspective view of a joint which may be employed.

In the drawings the numeral 1 indicates the longitudinal girders of an airship, and 2 are the transverse rings or frames.

According to the arrangement shown in Figs. 1 and 2, the outer cover is drawn in by means of tautening lines or the like 3 extending transversely to the longitudinal girders or members of the hull framework of the airship, and connected with the longitudinal girders as at 4, and with the cover 5 as at 6 between the longitudinal girders. The points at which the cover is pulled in may lie in rows running parallel or approximately parallel to the longitudinal girders. Any number of such rows of attachment points may be chosen, for example, one row only spaced midway between each two adjacent longitudinal girders may be used as shown in Fig. 1, or two rows spaced equi-distant from one another and from the nearest girder may be used as shown in Fig. 2.

Various arrangements for attaching the tautening lines to the cover may be employed. For example, each transverse line may be continuous from one longitudinal girder to another and connected at one or more points with each cover fabric panel.

Auxiliary girders, tubes, or other stiff members 7 may be secured, parallel to the main longitudinal girders of the airship, along the rows of points for attachment of the tautening lines, such stiffening members not being an integral part of the framework of the ship.

The spacing of the tautening lines 3 in a direction longitudinal of the airship is chosen

to be appropriate to the stiffness of the auxiliary members 7. Thus, it is possible to have a large number of tautening lines closely spaced with stiffening members which are relatively weak with regard to their resistance to bending, or to have stiffer auxiliary members and fewer tautening lines.

The tautening lines may be tightened by any suitable means, as by means of tension screws 3^a (Figs. 1 and 3) or the like inserted in them.

According to another arrangement shown in Figs. 3 and 4, the outer cover is forced out by means of auxiliary girders or other stiffening members 8 lying parallel to the main longitudinal girders of the airship on the inner side of the cover 5 and on the outer side of the tautening lines 3. The stiff girders or members 8, which may be termed tautening or reefing booms, may be arranged with any number in each panel, one being employed in Fig. 3 and two being employed in Fig. 4.

Any convenient arrangement of tautening lines may be employed. The tautening lines may be attached to the reefing booms 8 or to kingposts or other similar projections 9 on the reefing booms. The projections give a better (i. e. a more acutely bent) lead to the tautening lines, without employing a reefing boom which is too deep and consequently unnecessarily heavy.

In the methods shown in Figs. 5-14 one or more intermediate longitudinal girders 10 may be built into the framework of the airship between the members of each pair of main longitudinal girders, and reefing booms may be arranged to pull in or push out the cover in each panel between an intermediate and a main longitudinal girder, or between two intermediate girders. For example, as shown in Figs. 5 and 6 one intermediate longitudinal girder may be built on to the transverse rings 2 and the cover 5 may be pulled in between adjacent main and intermediate longitudinal girders by transverse tautening lines 3, attached to the cover at one or more points 6 between the intermediate and main longitudinal girders.

According to another feature of the invention the tautening lines may be arranged to run freely through the points of connection with the cover, and may be tautened at one point in a panel. By passing the tautening lines through pulleys from one panel to the next in the same vertical plane, they may be carried completely around the ship and tautened at a single convenient point in the lower portion of the framework.

According to a previous invention of the present applicants described in United States patent specification Serial No. 745,464, airships may be constructed with transverse frames 2 built in the form of a continuous trussed structure of triangular or prismatic cross section. In such an airship the junc-

tion points 11 (Fig. 6) of these transverse frames with the main longitudinal girders 1 form a convenient point of attachment for the tautening lines.

The tautening lines may be carried from these junction points to the auxiliary members 7, the reefing booms 8, or the intermediate longitudinal members or the like 10 in a variety of ways. For example, the tautening lines may run from one transverse frame 75 junction to a reefing boom or the like, diagonally (Figs. 7 and 8) or perpendicularly (Figs. 8, 9 and 10), and may run from one reefing boom to another perpendicularly, in pairs close together (Fig. 8) or spaced apart 80 (Figs. 9 and 10).

The reefing booms 8 or intermediate longitudinals 10 may be continuous along the whole length of the airship, or may be discontinuous at points along their length. The points 12 at which discontinuity occurs may be made to coincide with the planes of the transverse frames 2 as shown in Fig. 9, or may be located midway between the planes of the adjacent transverse frames 2 as shown in Figs. 10 and 11, and these points may coincide with the points of zero bending moment on the reefing booms as a whole, or at any other convenient point. The dotted graph in Fig. 11^a represents the bending moment diagram.

0 is the datum line, +x and -x are positive and negative flexures, and 13 are the points of contraflexure zero bending moments.

According to another feature of the invention, readily detachable joints or couplings may be provided at the points of discontinuity of the reefing booms to facilitate erection. These joints or couplings may be of a type which resists shear and torsion in the reefing booms, but will not resist bending. For example, as shown in Fig. 12, the joints or couplings may consist of ears 14 of flat metal secured to and projecting laterally at the end of each adjacent reefing boom, the ears of one boom being riveted or otherwise secured, as at 15, to the ears on the other boom.

According to another feature of the invention, the tautening wires 3 may be dispensed with and the reefing booms 10 may be forced outwards by screw jacks or other mechanical means 16 attached to the transverse frame 2 and arranged in one or more rows between adjacent main longitudinal girders 1, as shown in Figs. 13 and 14.

In any of the above arrangements the outer cover 5 may be attached to the reefing booms where it is in contact with them, or it may be left free, and the reefing booms may be stabilized against tilting in a transverse direction by means of independent lines, or bands of fabric connecting them with the main longitudinal girders.

It may be necessary to provide additional stiffness in the outer cover in certain local 130

areas, as for example in the wake of propellers. This may be done by means of light auxiliary girders connected with the reefing booms and/or with the main longitudinal girders. Alternatively, a double layer of fabric may be provided, the space between the two layers being airtight. Into this space air is blown by means of a scoop, mechanical blower or other similar device, so that an air cushion is formed in the cover which resists any flapping which might otherwise arise from the slipstream of the propellers or from any other similar cause.

The main longitudinal girders and other longitudinal members forming part of the framework or otherwise, may be constructed of triangular cross section.

Having thus described the nature of the said invention and the best means we know of carrying the same into practical effect, we claim:—

1. In an airship embodying a hull framework and a cover fabric stretched thereover, means for tautening the cover fabric, said means acting to force the cover fabric in a direction transverse to its surface relative to the hull framework.

2. In an airship embodying a hull framework and a cover fabric stretched thereover, mechanical means for tautening the cover fabric, said means forcing the fabric in a direction normal to its surface.

3. In an airship embodying a hull framework and a cover fabric stretched over the hull framework, transverse tautening lines connected with the cover fabric at points lying in rows running substantially parallel to the longitudinal girders of the hull framework and adapted to force the cover fabric in a direction normal to its surface.

4. An airship as claimed in claim 3, wherein stiffening members are arranged along the rows of points of connection of the tautening lines with the fabric.

45 5. In an airship embodying a hull frame-

work including longitudinal girders, and having a cover fabric stretched over said framework, longitudinal members located intermediate of the main longitudinal girders of the framework and inside the cover fabric, and mechanical means for tightening the cover fabric upon said longitudinal members.

6. An airship having a cover fabric stretched over a hull framework formed of transverse frame and longitudinal girders, and means including longitudinal booms for tightening the cover fabric over the framework.

7. In an airship embodying a hull framework including main longitudinal girders and having a cover fabric stretched over the hull framework, discontinuous longitudinal members located intermediate of the main longitudinal girders of the framework and inside the cover fabric, and mechanical means for tightening the cover fabric upon said longitudinal members.

8. An airship having a cover fabric stretched over the hull framework, discontinuous longitudinal members located intermediate of the main longitudinal girders of the framework and inside the cover fabric, mechanical means for tightening the cover fabric upon said longitudinal members, and joints connecting adjacent sections of said discontinuous longitudinal members adapted to resist shear and torsion but not resistant to bending.

9. An airship having a cover fabric attached to the hull framework and mechanical means for forcing said cover fabric in a direction normal to its surface to tighten said cover fabric, said cover fabric being in part of double thickness to form an air-containing cellular space.

In testimony whereof we have signed our names to this specification.

VINCENT CRANE RICHMOND.
